UNITED STATES PATENT OFFICE.

JOHN SAUNDERS, OF MANAYUNK, PHILADELPHIA, ASSIGNOR OF ONE-HALF
TO FRANCIS JOSEPH OBERT, OF READING, PENNSYLVANIA.

SLIDE-VALVE GATE FOR PAPER-PULP DIGESTERS, &c.

SPECIFICATION forming part of Letters Patent No. 234,431, dated November 16, 1880.

Application filed June 9, 1880. (No model.)

To all whom it may concern:

Be it known that I, JOHN SAUNDERS, of Manayunk, in the city and county of Philadelphia, State of Pennsylvania, have invented 5
a new and useful Improvement in the Construction of Slide-Valve Gates for Pulp-Digesters, and for vessels to contain oils, acids, or alkalies where a perfectly tight valve is required under any pressure, of which the following is a specification.

This improvement relates more particularly to valves working in a thick, viscous, and fibrous fluid, where it is necessary that the valve should at all times be kept in contact 15 with the face.

Various styles of valves have been used for the purpose of emptying paper-pulp tanks or digesters, coal-oil, acid, or alkaline tanks; but up to this time there has been no valve giving 20 satisfaction, as they all would clog or leak; and when this occurred it was necessary to take the valve apart, clear it of obstructions, or refit it before replacing the parts. This not only occupied time, but cost money to do, besides throwing the machinery out of use while 25 the clearing or refitting of the valve was going on. By my arrangement of valve all this annoyance is stopped.

Referring to the drawings, in which similar 30 letters refer to similar parts, Figure 1 is a perspective view of the valve-case and its accessories. Fig. 2 is a longitudinal sectional elevation. Fig. 3 is a cross-section through the center of the valve and case, also a perspective 35 view of the valve, rod, and loose collar.

A represents the case; A', the cap; B, the branch to the case; B', the branch on the cap; C, a bracket-arm for carrying the valve-rod screw; D, a wrought-iron yoke to retain the 40 wedges in adjustment; E, stuffing-boxes and glands to prevent blowing and leakage; F, enlargement of the valve-rod for screw-thread; G, nut formed by the head of the bracket; H, hand-wheel for moving the valve; J, screwed 45 tangs forged on the lower wedges or inclines; K, jam-nuts securing the wedges after adjustment to the yoke; L, upper wedge, on the back of which the valve slides; M, lower wedge, resting upon the inner face of the case; N, 50 valve provided with ears P P and loose collar P'. The fore and aft ends of the valve are

formed at an acute angle, so that in its travel over the opening to close the same it shall, in conjunction with the edge of the opening, act as a shear, cutting off any fibrous matter 55 which it may intercept, thus keeping the face clear.

The wedges L and M are so arranged that when the incline faces are placed together their backs shall be parallel with relation to the 60 valve-face and each other. The upper wedge is made slightly longer than the inside of the case, (the case being rabbeted at the ends to form pockets for the wedges,) and is free to move vertically. The lower wedge, M, has a 65 tang formed at its smaller end, the body of the wedge being about one-third less in length than the inside of the case, the tang J being projected through the case, and made of such length that when the butt of the wedge is 70 placed against the inside of the case opposite to the tang stuffing-box it shall project through the wrought-iron yoke D. The outer end of the tang is screw-threaded from its end to the stuffing-box gland, and is provided with double nuts K K, one each side of the yoke. These 75 nuts are for the easy adjustment of the valve to the face, so that while kept tight it shall still work freely thereon.

The valve having been placed in the case, 80 (while resting upon the branch flange B,) the wedges L are laid upon it at the sides. The wedges M are then put in place upon the wedges L, inclined faces together, with the screwed tangs projecting through the case. The bracket-arm C being in place, the threaded valve-rod F is screwed into the nut G, and with the plain part of the rod into and through the stuffing-box in the case until the valve N is reached. The collar P' is then placed between the ears P, 85 and the valve-rod passed through the ears and collar, being secured in the latter by a pin or key. This permits the revolution of the screw and the progression of the valve in either direction upon the valve-face. The cap A' is now 90 bolted upon the case A with its face or planed ledges on the same in contact with the back of the wedges M, thus binding the valve N tightly against the valve-face. As wear occurs 95 between the two surfaces the inside nuts K are slackened and the outside nuts K tightened. 100 This draws the faces together. The inside nuts

are again tightened, and the valve is ready for operating.

If deemed necessary for special cases, the valve-face may be faced with cast-steel and the valve be cast of or be faced with the same material, when it can be closed and kept tight, although passing viscous fluids interspersed with woody fibers.

I am aware that wedges for the purpose of securing a tight fit between the valve and its face are not new, (see patent of W. Glass, November 8, 1870, No. 109,001, stop-cock;) but in all the cases coming under my notice the wedges are brought into action just as the valve closes the opening. This does very well for limpid fluids, but will not do where viscous or fibrous fluids are to be passed.

Having shown the construction and described the use of my invention, what I claim, and for which I desire to obtain Letters Patent of the United States, is as follows, to wit:

1. The combination of the slide-valve N with the valve-easing A, plain wedges L, and tanged

wedges M, substantially as specified, and for the purpose described.

2. In combination, the wedges L and M, with the slide-valve N, case A, yoke D, and nuts K, substantially as shown, and for the purpose specified.

3. In combination, the yoke D and case A, with tanged wedges M and nuts K, for the purpose described.

4. In combination, the enlarged valve-rod F, with hand-wheel H, bracket-arm nut G, case A, valve N, and collar P', for the purpose specified.

5. The valve N, with its advancing ends bevelled to form a cutting-edge, in combination with the inner edges of the opening covered by the valve, for the purpose described, and substantially as shown.

JOHN SAUNDERS.
